(73) Assignee: **Sanyo Electric Co., Ltd.**, Osaka-fu (JP)

(57) **CLAIM**

(**) Term: **14 Years**

The ornamental design for an automatic tablet bottling machine, as shown.

DESCRIPTION

(21) Appl. No.: **29/131,688**

(22) Filed: **Oct. 26, 2000**

(30) **Foreign Application Priority Data**

Apr. 27, 2000 (JP) 12-011257

(51) **LOC (7) Cl.** **10-04**

(52) **U.S. Cl.** **D10/97; D24/111**

(58) **Field of Search** D10/97; D24/111;

414/403, 675; 453/30, 33, 58; 222/57, 190;
210/169; 221/13, 272; 422/268

(56) **References Cited**

FIG. 1 is a perspective view of automatic tablet bottling machine looking from the upper left-side direction thereof;

FIG. 2 is a front view thereof;

FIG. 3 is a top view thereof;

FIG. 4 is a right-side view thereof;

FIG. 5 is a left-side view thereof;

FIG. 6 is a rear view thereof;

FIG. 7 is a bottom view thereof; and,

FIG. 8 is a perspective view of automatic tablet bottling machine showing the state of use thereof.
